LINT CLEANING APPARATUS

Albert S. McGinnis and Harry Berry, Cairo, Ill.,
assignors to Industrial Patents Corporation,
Chicago, Ill., a corporation of Delaware

Application July 20, 1945, Serial No. 606,141

4 Claims. (Cl. 19—72)

1

This invention relates to improvements in fiber processing apparatus and has particular reference to improved apparatus for cleaning fiber such as cottonseed lint by freeing the fiber of particles of seed hull, shale and other foreign matter.

In the cleaning of cottonseed lint it is known to use a cyclone separator in a conduit line through which the lint is forced by air pressure or suction. It has also been known to interpose a baffle separator between the discharge of such a cyclone separator and the intake line of a suction fan which draws the lint from the cyclone. While a large amount of debris can be thus removed from the lint it has been found that in many cases the lint is still not clean enough to meet the exacting requirements for a high quality product which commands the top market prices.

The industry has thus been faced for a long period of time with the problem of removing from the lint the smaller and lighter pieces of debris entrained with the lint after it passes through the conventional cyclone and baffle separators in order to provide a clean, high quality product, and, to the best of our knowledge, no adequate solution to this problem has been previously proposed.

It has been found, however, that by inserting a special baffle separator in the suction line through which the lint is moved from the conventional separator already in use, a clean, high quality product can be produced at no additional cost and with only a small, simple and inexpensive addition to the lint cleaning apparatus.

It is thus a major object of the present invention to provide, in combination with the conventional separators used in lint cleaning apparatus, a special separator interposed in the suction line through which the lint is moved from the conventional separators to remove from the lint substantially all of the residual debris and especially small and light pieces not eliminated by the conventional separators, to thus provide a high quality lint product for those uses wherein especially clean lint is required.

A still further object resides in the provision of improved cottonseed lint cleaning apparatus which cleans the lint of substantially all debris such as particles of hull and shale and also provides beating action in addition to that provided by the conventional cleaning apparatus to provide an improved texture of the product.

A still further object resides in the provision of improved cottonseed lint cleaning apparatus which produces a clean, high quality lint product, and which is economical to manufacture and in-

2

stall and involves no appreciable additional operating expense.

Other objects and advantages will be apparent from the following description in connection with the accompanying drawings and from the appended claims.

In the accompanying drawings in which like reference numerals are used to designate similar parts throughout:

10 Figure 1 is a diagrammatic elevational view of a cottonseed lint cleaning apparatus constructed according to the invention;

15 Figure 2 is a perspective view of a baffle separator constituting a part of the lint cleaning apparatus shown in Figure 1, a portion being broken away to better illustrate the construction thereof; and

20 Figure 3 is a perspective view of another baffle separator also constituting a portion of the lint cleaning apparatus shown in Figure 1, a portion being broken away to better illustrate the construction thereof.

25 With continued reference to the drawings and particularly to Figure 1, the numeral 10 generally indicates a conventional cyclone separator into which the lint is conducted through the inlet conduit 12 and from which it is conducted through the discharge conduit 14.

30 As cyclone separators are commonly used and well known in the art, a detailed description is not considered necessary for the present disclosure.

35 The lint leaving the cyclone separator through the discharge conduit 14 entrains a considerable amount of debris, mostly in the form of broken hulls and pieces of shale, but which may include small amounts of other foreign material.

40 In order to provide a marketable product it is necessary to remove this debris from the lint and this is accomplished by passing the lint through baffle separators after it leaves the cyclone separator. As mentioned above, it has been common practice to provide a single baffle-type separator, such as is indicated at 16 in Figure 1, connected

45 to the end of the discharge conduit 14, but it has been found that the lint leaving such a baffle separator still entrains a sufficient amount of debris to cause frequent rejections of the lint from the higher grade classes of lint product, which difficulty has been overcome in the present invention by the provision of a second baffle separator, generally indicated at 18, interposed in the suction line 20 which extends from the separator 16 to a fan 22 which is operative to remove the lint from

50 55 the separator 16.

The separator 16 is particularly illustrated in Figure 2 and may comprise a casing 24 of generally rectangular cross section having at one side thereof an extension 26 of generally triangular vertical cross section. The upper end of the casing 24 is tapered from a generally square to a circular section, as indicated at 28, to fit the lower end of the discharge duct 14, and within the casing, immediately below the tapered portion there is provided a transverse baffle 30 which slants toward the side of the casing, opposite the extension 26, and has a rod-like pivotal support 32 which lies closely adjacent to the side of the casing carrying the extension 26.

Below the baffle 30 there is a second baffle 34 mounted on a rod-like support 36 which is disposed closely adjacent to the side of the casing opposite the extension 26 and the baffle is inclined downwardly and toward the extension 26.

Immediately below the lower edge of the baffle 30 the casing 24 is provided in the wall opposite extension 26 with a transverse slot 38. This slot has a length substantially equal to the width of the casing wall and a limited height, a height of one inch having been found satisfactory, the height of the slot, however, is controlled by a slide of more or less conventional form such as is illustrated at 40 in Figure 3, so that the total area of the slot can be adjusted as may be found necessary or desirable.

A suction pipe connection 42 is connected into the casing 24 just above the flat, generally horizontal, upper surface 44 of the extension 26. This connection 42 is preferably a sheet metal member of generally rectangular cross section and is inclined outwardly and upwardly from the corresponding side of the wall of the casing 24 with its center line at an angle of approximately 45° from the center line of the discharge pipe 14, although the inclination of the suction pipe to the discharge pipe is not critical and may be varied within reasonable limits without in any way exceeding the scope of the invention.

The lower edge of the suction pipe connection 42 is spaced above the adjacent edge of the extension top 44 and the space between the adjacent edges of the connection 42 and the top 44 is left open to provide a transverse slot 46 in the corresponding side wall of the casing 24, this slot having a length substantially equal to the width of the casing of the side wall, and a height of approximately one inch. The edge of the top 44 adjacent the side wall of the casing is cut away to provide a slot 48 which is in effect a continuation of the slot 46 and has a length substantially equal to the width of the casing 24 and a depth of approximately two inches, extending into the top 44 of the extension. Within the casing 24, and located at the inner edge of the top 44, there is a trough-shaped member 50 disposed adjacent to the lower edge of the baffle 34.

As the lint with the entrained debris is discharged from the cyclone separator 10 and flows into the separator 16 it strikes the upper baffle 30 and is diverted toward the rear wall of the baffle separator which is the wall remote from the extension 26. As the lint flows over the lower edge of the baffle 30, the heavier portions of the debris are thrown outwardly toward the rear wall of the casing and some of the debris will fall downwardly through the slot 38. As the lint flows past the lower edge of the baffle 30, its direction of movement is sharply changed and it then impinges on the baffle 34 where an additional amount of debris is thrown downwardly toward

the baffle. This debris flows through the space between the lower edge of the baffle 34 and the trough-shaped member 50 and is discharged into the lower portion of the separator 16 which, with the extension 26, constitutes a hopper for the debris falling over the lower edge of the baffle 34. The lower end of this hopper is closed by a suitable gate or valve member 52 which may be opened at suitable intervals to discharge the contents of the hopper into a waste can 54.

The slot 38 and combined slot 46-48, serve to control the amount of suction applied to the moving mass or column of lint by the fan 22 and, also, assist in separating debris from the lint, particularly the slot 38. Because of the lower pressure inside the separator 16 some air will flow into the separator through the slot 38 which flow is sufficient to prevent the light lint from being kicked out through the slot but is not sufficient to prevent discharge of heavier particles of debris through the slot as the travel of the lint is sharply curved about the lower edge of the baffle 30.

The suction pipe connection 42 is connected at its outer end with the lower end of the second baffle separator 18, the upper end of which is connected through suction pipe 20 with the intake of fan 22.

The second baffle separator 18 is particularly illustrated in Figure 3, and is of generally rectangular cross section and is provided with end portions which change the rectangular section to circular section as indicated at 56 and 58. In the operative position shown in Figure 1, this separator has an upper side 60 and a lower side 62. Three baffles, 64, 66, and 68 are mounted in the separator casing 70 with their respective rod-like supports adjacent the upper side of the wall 60. Of these baffles, the central or intermediate baffle 66 is positioned at substantially the mid-length location of the casing 70 while the end baffles 64 and 68, are located near the ends of the casing.

Two baffles, 72 and 74, are positioned transversely of the casing 70 with their rod-like supports adjacent the lower side 62 of the casing and are located in staggered relation with respect to the upper baffles 64, 66 and 68. Thus the baffle 72 is substantially mid-way between the baffles 66 and 68. All of the baffles, including those in the separator 16, are inclined in the direction of air flow through the separators and are adjustable. Each baffle is held in adjusted position by a suitable radial lever member as indicated at 76 for the baffle 64 and a cooperating curved detent member 78. The adjusting levers for the baffles 66, 68, 72 and 74 are indicated at 79, 80, 82, and 84 respectively.

The upper side wall of the casing 70 is provided with two adjustable slots, as indicated at 86 and 88 in Figure 1. The slot 86 is disposed substantially mid-way between the pivoted edges of the baffles 64 and 66 and the slot 88 is disposed substantially mid-way between the pivoted edges of the baffles 66 and 68. While this has been found to provide a satisfactory operative arrangement, the exact location of these slots is not critical and may be varied within reasonable limits without exceeding the scope of the invention.

The bottom side wall of the casing 70 is provided with two slots as indicated at 90 and 92. The slot 90 is located closely adjacent the pivoted edge of the baffle 72 on the upstream side of the baffle and the slot 92 is correspondingly located

closely adjacent to the pivoted edge of the baffle 74. The location of the slots 90 and 92 relative to the baffles 72 and 74 is critical within closer limits than is the relative location of the slots 86 and 88.

Each of the slots may be conveniently constructed in accordance with the illustrated arrangement of the slot 88 in Figure 3. According to this construction an elongated aperture is provided in the side wall of the casing, the aperture being transverse to the side wall and substantially perpendicular to the side wall center line and having a length substantially equal to the width of the side wall and a width of approximately one inch, although the width may be varied without exceeding the scope of the invention. The area of the slot is rendered adjustable by the provision of a slide or shutter member, as indicated at 40, which extends across the side wall adjacent the aperture and has its ends slidably secured in a pair of opposed guide members 94 and 96, each of which may comprise an angle member having one side secured to the corresponding vertical side wall of the casing and another portion overlapping and spaced from the corresponding apertured casing wall by an amount sufficient to permit the slide member to move freely in the end guides thus provided.

As the lint leaves the separator 16 through the suction pipe connection 42 with its residual amount of entrained debris, it first strikes the baffle 64 and is deflected downwardly toward the slot 90 through which a portion of the residual debris is discharged to the outside of separator 18. The baffle 72 then deflects the lint upwardly toward the slot 86 through which a portion of the remaining debris may be discharged and the baffle 66 again deflects the lint downwardly toward the slot 92 through which additional debris, if any is still entrained, may be discharged. The baffle 74 then deflects the lint upwardly toward the slot 88, through which additional debris may be discharged, the baffle 68 deflecting the lint downwardly again and straightens its direction of travel through the suction pipe 20. The major portion of the debris separated in the separator 18 will be discharged through the lower side slots 90 and 92, the upper side slots 86 and 88 being provided principally to control the suction in the separator and to direct generally transverse cleaning air streams through the body of lint moving through the separator. The slots in the separator 18 operate in the same manner as the slot 38 in the separator 16, the air flowing inwardly through the slots because of the lower pressure within the separator, tending to prevent the lint from kicking out through the slots while having insufficient velocity to prevent the discharge of the heavier particles of debris through the slots as the direction of travel of the lint is sharply changed in the vicinity of the slots. The baffles in the separator 18 also provide a strong beating action on the lint which tends to fluff the lint and work the fibers together to form a continuous body of clean lint fiber emerging from the separator.

The invention provides a greatly improved method which subjects the lint to a beating and cleaning action in baffle separators arranged in series and to the effect of transverse air currents, so that not only the heavier and coarser part of the debris, such as hull fragments and shale particles, entrained with the lint is removed, but also the smaller and lighter portions of debris which

were formerly left in the lint after completion of the conventional cleaning operation are also eliminated.

The improved method provides a double beating and cleaning action while the lint is subjected to low air pressure and the multiple baffle unit, second in the series of baffle cleaners, not only thoroughly cleans the lint but intermingles the fibers in a manner which produces a fluffy and continuous body of lint at the termination of the improved cleaning method.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and language of equivalency of the claims are therefore intended to be embraced therein.

Obviously, many modifications and variations of the invention hereinbefore set forth may be made without departing from the spirit and scope thereof, and, therefore, only such limitations should be imposed as are indicated in the appended claims.

We claim:

30 1. A cottonseed lint cleaning apparatus including baffle means in a suction line through which the lint is moved by suitable suction means, said suction line being formed in part of an elongated tubular member having an upper and lower side when in operative position, oppositely disposed sets of baffles in said tubular member, one set of baffles being disposed along said upper side, the other set of baffles being disposed along said lower side, the upper side of said member being provided with slots between adjacent baffles, and the lower side of said member being provided with slots adjacent to the front edges of the corresponding baffles.

45 2. A cottonseed lint cleaning apparatus including a suction line, baffle means in said suction line through which the lint is moved by suitable suction means, said suction line being disposed at approximately 45° with respect to the horizontal when in operative position with the inlet end lowermost, said suction line being formed in part of an elongated tubular member having an upper and lower side when in operative position, oppositely disposed sets of baffles in said tubular member, one set of baffles being disposed along said upper side, the other set of baffles being disposed along said lower side, the upper side of said member being provided with slots between adjacent baffles, and the lower side of said member being provided with slots adjacent to the front edges of the corresponding baffles.

55 3. A cottonseed lint cleaning apparatus including baffle means in a suction line through which the lint is moved by suitable suction means, said suction line being formed in part of an elongated tubular member having an upper and lower side when in operative position, oppositely disposed sets of baffles in said tubular member, one set of baffles being disposed along said upper side, the other set of baffles being disposed along said lower side, the upper side of said member being provided with slots between adjacent baffles, the lower side of said member being provided with slots adjacent to the front edges of the corresponding baffles, said slots extending transversely across the upper and lower sides of said suc-

tion line, and means to adjust the width of said slots.

4. A cottonseed lint cleaning apparatus to be used in association with a cyclone separator and including a hopper disposed vertically below the separator, and a suction line connected to the hopper through which the lint is moved by suitable suction means, said hopper having baffle means therein to direct the lint falling vertically therethrough in a tortuous path, slots in the walls of said hopper adjacent said baffles, said baffles being arranged in association with said suction line to turn the lint stream sharply through a relatively wide angle whereby to centrifugally throw the heavier particles in the lint stream outwardly just before the stream enters the suction line, said suction line being formed in part of an elongated tubular member having an upper and lower side when in operative position, oppositely disposed sets of baffles in said tubular member, 20 one set of baffles being disposed along said upper side, the other set of baffles being disposed along

said lower side, the upper side of said member being provided with slots between adjacent baffles, and the lower side of said member being provided with slots adjacent to the front edges of the corresponding baffles.
